UNITED STATES PATENT OFFICE

2,406,271

BASE FOR ELECTRIC LAMPS OR
SIMILAR DEVICESIrving H. Van Horn, East Cleveland, Ohio, assignor
to General Electric Company, a corporation
of New York

Application January 30, 1942, Serial No. 428,863

15 Claims. (Cl. 176—32)

1

My invention relates to electric lamps and similar devices comprising a bulb containing an electric energy translation element and having a base secured to said bulb. More particularly, the invention relates to shock-proof base structures for such lamps and similar devices.

An object of my invention is to provide a resilient connection between the bulb and the portion of the base which engages with a socket so that shocks transmitted to the socket will be damped before they reach the critical parts of the lamp or similar device in the socket. Another object is to provide a shock-proof base which will fit in an ordinary socket. Further objects and advantages of my invention will appear from the following description of species thereof and from the drawing.

In the drawing, Figs. 1-3 are elevations, in section, of three modifications of base structures comprising my invention.

Referring to Fig. 1, the lamp or similar device comprises a glass bulb 10 having a neck portion 11 and a pair of lead wires 12 and 13 extending from a stem of the usual tipless construction provided with the usual exhaust tube 14.

The bulb 10 is provided with a base comprising a cylindrical metal shell or body portion 17 which, in this instance, is part of a conventional screw threaded type of base including an eyelet 18 which serves as the end contact and is secured to the outer end of the shell 17 through the medium of glass insulation 19.

In accordance with my invention, the shell 17 is connected to the bulb by a resilient skirt or sleeve member 20 which may be made of rubber or allied materials, preferably a high temperature synthetic rubber. The lower or outer end of the said skirt member 20 is provided with screw threads and is threaded into the shell 17 while its annular upper or inner end surrounds the bulb neck 11 and is secured thereto by the usual basing cement 16. The said sleeve or skirt member 20 may be secured firmly within the inner end of the shell 17 by a comparatively thin layer of cement or other adhesive 21, some of which is pushed down into the lower part of the base, as shown. In the form shown in Fig. 1, the lower end of the skirt or sleeve member 20 is closed except for two openings 22. The lead wires 12 and 13 extend through said openings, the wire 12 being soldered to the end contact 18 while the lead wire 13 extends upwardly between the shell 17 and skirt 20 and is soldered to the exterior of the shell 17 at the point 23.

In use, the base 17 is screwed into an ordinary

2

screw threaded socket and upon transmission of a shock thereto the bulb 10 is permitted, by the resilient skirt 20, to rock with respect to the said base 17 so that the shock is damped before it can result in destructive injury to the filament and other parts, such as glass parts, in the bulb 10, or to the basing cement. Tests have shown that even extremely violent shocks are successfully damped by such a base structure.

If desired, the base 17 may be of any other known type, such as the ordinary bayonet base which has a cylindrical shell and a pair of pins extending laterally therefrom. Moreover, the rubber skirt 20 may, of course, be molded directly into the base shell 17. The cement 21 may be eliminated, and if desired, any possible relative turning between the shell 17 and skirt 20 may be prevented by suitable protuberances or indentations in the shell 17 which fit in matching indentations or protuberances in the skirt member 20. It will be noted that a small amount of slack is left in the lead wires 12 and 13 so as to permit the bulb 10 to rock freely with respect to the base 17. If desired, the inner surface of the skirt 20 surrounding the bulb neck may be roughened or provided with screw threads (as in Fig. 2) to provide a better gripping action for the cement 16.

The structure shown in Fig. 2 is similar to that shown in Fig. 1. However, in this instance, the bulb neck is provided with an open bottomed screw threaded base shell 15 which is cemented to the bulb neck at 16 and the skirt member 20' is provided with corresponding internal screw threads. In this case, it is also preferable that a thin layer of cement or other adhesive be applied between the threads in the skirt 20' and on the shell 15. Another minor distinction is the provision of a single axial passage 22' in the bottom of the skirt 20' through which both of the lead wires 12 and 13 extend. In order to prevent short circuiting, the lead wire 12 is provided with a surrounding tube 24 of suitable flexible insulating material; for example, glass wool, asbestos, synthetic spaghetti, etc. The lamp is completed by a base 17 like that shown in Fig. 1. If desired, the shell 15 may, of course, be made cylindrical, instead of screw threaded.

Referring to Fig. 3, the structure shown therein employs an ordinary screw threaded base 17 like that employed in the Fig. 1 and 2 modifications and a screw threaded shell 15 like that shown in Fig. 2. However, in this instance, the rubber sleeve or skirt member 20 or 20' is replaced by a resilient helical wire spring mem-

ber 20a, preferably made of steel or a spring alloy. The said spring 20a is screwed into the interior of the base 17 and onto the exterior of the shell 15. The said spring may be secured within the base 17 by a quantity of solder 25. In order that the spring 20a may be readily screwed into the base 17, it may be provided with a lateral or radial extension 26 at its lower end. In this design, the lead wire 13 is connected to the upper shell 15. Electrical connection is furnished by the spring 20a between the lead wire 13 and the base shell 17. The spring 20a functions in a manner analogous to that of the rubber sleeve or skirt member 20 or 20' in Figs. 1 and 2. Once screwed into the spring 20a, the shell 15 is prevented from unscrewing therefrom by contraction or tightening of the spring upon attempting to unscrew the said shell. Obviously, in the constructions shown in the drawing, the rubber skirt 20 or 20', or the spring 20a, forms a cushion which is flexible in all directions so that the base is characterized by the absence of any unyielding connections between the shell 17 and the bulb 10.

It will be obvious to those skilled in the art that various substitutions, changes and omissions may be made in the structures illustrated without departing from the spirit of my invention. It will be obvious that the invention is useful for electric incandescent or discharge lamps or for other similar devices such as radio tubes which may be subjected to extremely severe shocks. In the case of an incandescent lamp, the filament mount structure may be similar to that now in common use in the so-called rough service lamps. In such lamps the mount comprises a glass arbor extending axially of the bulb 10 from the stem and having a plurality of outwardly radiating support wires which support a coiled filament. If desired, the shell 15 in Fig. 3 may be eliminated by molding screw threads in the bulb neck 11 corresponding to the screw threads of the said shell 15; in this event, some means, such as cement may be employed to hold the spring on the glass bulb neck. Moreover, in the form shown in Fig. 3, the spring 20a may be screwed on to the exterior of the base shell 17; in this case, the said shell is preferably elongated somewhat so that the spring is screwed on to only the upper portion thereof to permit the lower portion to be readily screwed into a standard socket.

What I claim as new and desire to secure by Letters Patent of the United States is:

1. An electrical device comprising a bulb containing an electric energy translation element and having a shock proof base secured to said bulb, said base comprising a metal shell fixedly secured to an end of said bulb, a second metal shell shaped to engage with a socket and being in end-to-end alignment with said first-mentioned shell and spaced therefrom, and a normally unrestrained resilient member interconnecting said shells to form a cushion which is flexible in all directions so that the said base is characterized by the absence of any unyielding connections between the said bulb and the second metal shell.

2. An electrical device comprising a bulb having a neck portion and containing an electric energy translation element and having a shock proof base secured to said neck portion, said base comprising a metal shell shaped to engage with a socket and being in axial alignment with said bulb neck portion and spaced

axially from the end thereof, and a normally unrestrained resilient member secured at one end to said shell and secured at its other end around said bulb neck to form a cushion which is flexible in all directions so that the said base is characterized by the absence of any unyielding connections between the said bulb and the metal shell.

3. An electrical device comprising a bulb having a neck portion and containing an electric energy translation element and having a shock proof base secured to said neck portion, said base comprising a metal shell shaped to engage with a socket and being in axial alignment with said bulb neck portion and spaced axially from the end thereof, and a resilient rubber sleeve member secured at one end to said shell and secured at its other end around said bulb neck to form a cushion which is flexible in all directions so that the said base is characterized by the absence of any unyielding connections between the said bulb and the metal shell.

4. An electrical device comprising a bulb having a neck portion and containing an electric energy translation element and having a shock proof base secured to said neck portion, said base comprising a metal shell shaped to engage with a socket and being in axial alignment with said bulb neck portion and spaced axially from the end thereof, and a normally unrestrained resilient helical wire spring member secured at one end to said shell and secured at its other end around said bulb neck to form a cushion which is flexible in all directions so that the said base is characterized by the absence of any unyielding connections between the said bulb and the metal shell.

5. An electrical device comprising a bulb containing an electric energy translation element and having a shock proof base secured to said bulb, said base comprising a metal shell fixedly secured to an end of said bulb, a second metal shell shaped to engage with a socket and being in end-to-end alignment with said first-mentioned shell and spaced therefrom, and a resilient rubber sleeve member secured at one end to the interior of said second-mentioned shell and secured at its other end around first-mentioned shell to form a cushion which is flexible in all directions so that the said base is characterized by the absence of any unyielding connections between the said bulb and the second metal shell.

6. An electrical device comprising a bulb containing an electric energy translation element and having a shock proof base secured to said bulb, said base comprising a metal shell fixedly secured to an end of said bulb, a second metal shell shaped to engage with a socket and being in end-to-end alignment with said first-mentioned shell and spaced therefrom, and a normally unrestrained resilient helical wire spring member secured at one end to the interior of said second-mentioned shell and secured at its other end around first-mentioned shell to form a cushion which is flexible in all directions so that the said base is characterized by the absence of any unyielding connections between the said bulb and the second metal shell.

7. An electrical device comprising a bulb containing an electric energy translation element and having a shock proof base secured to said bulb, said base comprising a screw-threaded metal shell fixedly secured to an end

of said bulb, a second screw-threaded metal shell shaped to engage with a socket and being in end-to-end alignment with said first-mentioned shell and spaced therefrom, and a normally unrestrained resilient member interconnecting said shells, said resilient member being threaded into the interior of said second-mentioned shell and around the exterior of said first-mentioned shell to form a cushion which is flexible in all directions so that the said base is characterized by the absence of any unyielding connections between the said bulb and the second metal shell.

8. An electrical device comprising a bulb containing an electric energy translation element and having a shock proof base secured to said bulb, said base comprising a screw-threaded metal shell fixedly secured to an end of said bulb, a second screw-threaded metal shell shaped to engage with a socket and being in end-to-end alignment with said first-mentioned shell and spaced therefrom, and a resilient rubber sleeve member interconnecting said shells, said resilient member being threaded into the interior of said second-mentioned shell and around the exterior of said first-mentioned shell to form a cushion which is flexible in all directions so that the said base is characterized by the absence of any unyielding connections between the said bulb and the second metal shell.

9. An electrical device comprising a bulb containing an electric energy translation element and having a shock proof base secured to said bulb, said base comprising a screw-threaded metal shell fixedly secured to an end of said bulb, a second screw-threaded metal shell shaped to engage with a socket and being in end-to-end alignment with said first-mentioned shell and spaced therefrom, and a normally unrestrained resilient helical wire spring member interconnecting said shells, said resilient member being threaded into the interior of said second-mentioned shell and around the exterior of said first-mentioned shell to form a cushion which is flexible in all directions so that the said base is characterized by the absence of any unyielding connections between the said bulb and the second metal shell.

10. An electrical device comprising a bulb containing an electric energy translation element and having a shock proof base secured to said bulb, said base comprising a hollow resilient rubber member having an enlarged cylindrical skirt portion surrounding and secured to an end portion of said bulb, said rubber member also having a shell-engaging portion of smaller diameter than said skirt portion extending outward from said skirt portion beyond the said end of the bulb, and a metal base shell shaped to engage in a socket and secured around said shell-engaging portion of the rubber member.

11. An electric lamp comprising a bulb having a sealed neck, a filament within the bulb having leads extending through the end of said neck, resilient shock-absorbing material circumposed about and firmly secured to the lower end of said neck, a base member having a generally cylindrical body portion formed with a screw-

threaded periphery, the inner end of the body portion being circumposed about and firmly secured to said shock-absorbing material and the outer end carrying a contact insulated from the body of said base, and means electrically connecting said leads with said body portion and contact member.

12. An electric lamp comprising a bulb having a sealed neck, a filament within the bulb having leads extending through the end of said neck, an elongate body of shock-absorbing material having an annular inner end portion circumposed about and firmly secured to the lower end of said neck, a base member having a generally cylindrical body portion formed with a screw-threaded periphery, the inner end of the body portion being circumposed about and firmly secured to said shock-absorbing material, and means electrically connecting said leads and base member.

13. An electric lamp comprising a bulb having a sealed neck, a filament within the bulb having leads extending through the end of said neck, resilient shock-absorbing material disposed about and firmly secured to the lower end of said neck, a base member having a generally cylindrical body portion formed with means on its outer periphery for securing it in a socket, the inner end of said body portion being disposed about and firmly secured to said shock-absorbing material and the outer end carrying a contact insulated from the body of said base, and means electrically connecting said leads with said body portion and contact member.

14. An electric lamp comprising a bulb having a sealed neck, a filament within the bulb having leads extending through the end of said neck, resilient shock-absorbing material disposed about and firmly secured to the lower end of said neck, a base member having a generally cylindrical body portion formed with means on its outer periphery for securing it in a socket, the inner end of said body portion being disposed about and firmly secured to said shock-absorbing material and the outer end carrying a contact insulated from the body of said base, means electrically connecting said leads with said body portion and contact member, said end of the neck of the bulb and said inner end of the base being separated longitudinally of the lamp by an intervening space and said material bridging said space.

15. An electric lamp comprising a bulb having a sealed neck, a filament within the bulb having leads extending through the end of said neck, resilient shock-absorbing material disposed about and firmly secured to the lower end of said neck, the base member having a generally cylindrical body portion formed with a screw-threaded periphery, the inner end of said body portion being disposed about and firmly secured to said shock-absorbing material and the outer end carrying a contact insulated from the body of said base, means electrically connecting said leads with said portion and contact member, said end of the neck of the bulb and said inner end of the base being separated longitudinally of the lamp by an intervening space and said material bridging said space.

IRVING H. VAN HORN.
